US0D1060189S

(12) **United States Design Patent** (10) **Patent No.:** **US D1,060,189 S**
(45) **Date of Patent:** **** Feb. 4, 2025**

(54) **SET OF STORAGE CUBBY INSERTS**

(71) Applicant: **GM Cruise Holdings LLC**, San Francisco, CA (US)

(72) Inventors: **Timothy Jon Meador**, Fairfield, CA (US); **Alexis DeStasio**, San Francisco, CA (US); **Matthew Martin**, Fairfax, CA (US)

(73) Assignee: **GM Cruise Holdings LLC**, San Francisco, CA (US)

(**) Term: **15 Years**

(21) Appl. No.: **29/819,797**

(22) Filed: **Dec. 17, 2021**

(51) LOC (15) Cl. **12-16**

(52) U.S. Cl.

USPC **D12/415**; D6/705

(57) **CLAIM**

The ornamental design for a set of storage cubby inserts, as shown and described.

DESCRIPTION

FIG. 1 is a front perspective view illustrating a set of storage cubby inserts design;

FIG. 2 is a front view illustrating a set of storage cubby inserts design;

FIG. 3 is a back view illustrating a set of storage cubby inserts design;

FIG. 4 is a side view illustrating a set of storage cubby inserts design according to one embodiment;

FIG. 5 is another side view illustrating a set of storage cubby inserts design;

FIG. 6 is a top view illustrating a set of storage cubby inserts design;

FIG. 7 is a bottom view illustrating a set of storage cubby inserts design; and,

FIG. 8 is an environmental view illustrating a set of storage cubby inserts design.

The broken line bracket in FIGS. 1-5 is for illustrative purposes only and forms no part of the claimed design. The broken lines showing the cabinet in FIG. 8 are included for the purpose of illustrating environment and forms no part of the claimed design.

1 Claim, 8 Drawing Sheets
